UNITED STATES PATENT OFFICE.

WILLIAM HEDGES TAYLOR, OF UPPER DARBY, PENNSYLVANIA, ASSIGNOR OF ONE-HALF TO MRS. A. R. KING, INCORPORATED, OF PHILADELPHIA, PENNSYLVANIA, A CORPORATION OF PENNSYLVANIA.

DIE FOR SHOE SOLES.

Application filed August 12, 1925. Serial No. 49,790.

To all whom it may concern:

Be it known that I, WILLIAM H. TAYLOR, a citizen of the United States, and resident of Upper Darby, in the county of Delaware and State of Pennsylvania, have invented certain new and useful Improvements in Dies for Shoe Soles, of which the following is a specification.

My present invention relates to a method 10 of building shoes and more specifically of applying a heel of the wood block type thereto.

The principal object of the invention is the saving of the initial amount of leather 15 used in the outsole, and second, in the saving of time necessary to apply the heel thereto.

To this end my invention contemplates the cutting out of the outsole in the manner 20 which instead of including a bulbous heel, will be replaced by a substantially arrow headed portion over which the wood block heel will be fitted. The utilization of an outsole of this shape makes a substantial 25 saving in the initial amount of leather required.

It has been the custom after the outsole is secured to the upper, that the wood block heel be placed in position by hand, the operator then taking a pencil or sharp instrument and marking the outline of the breast of the heel upon the outsole, removing the heel, and with a knife trimming that portion of the sole overlying the heel to form a 35 tail piece, then applying the heel and securing the same by the usual glue, nail or screws.

This invention further contemplates the use of a blade for automatically cutting the 40 tail piece from the outsole in order to save this hand operation and thereby cheapen the cost of the shoe.

To this end the invention includes an anvil of metal which is adapted to be slipped 45 beneath the loose heel of the outsole, and a blade of the proper contour which includes the curvature of the heel breast and the outline of the tail piece, and cutting the leather with this blade while resting upon the anvil, all of which is done automatically and in much less time than if these operations 50 were performed by hand.

My invention further consists in the ar-

rangement, construction and combination of parts hereinafter shown and described. 55

I have illustrated in the accompanying drawings a preferred form of the invention, although obviously I do not wish to be limited thereto.

In these drawings:—

Fig. 1 is a front elevation of a device used to reciprocate the shoe against the anvil and knife. Fig. 2 is a composite view in perspective of a heel and heel portion of the shoe. Fig. 3 is a plan view of the shoe sole. Fig. 4 is a plan view of the anvil. Fig. 5 is a side elevation of the device of Fig. 4. Fig. 6 is a sectional view along the line 6—6 of Fig. 4. Fig. 7 is a sectional view along the line 7—7 of Fig. 4. Fig. 8 is a front 70 elevation of the knife, and Fig. 9 is a top plan view of the device of Fig. 8.

Referring now with particularity to the embodiment illustrated, I have shown an outsole as consisting of a toe portion 1, a 75 heel portion 2, and a joining neck portion 3. It will be noted that the heel portion 2 is of substantially arrow shape and contour, the normal outline of the usual heel of an outsole being shown in dotted lines at 80 4. Obviously by using a heel having the contour as shown at 2, all of the leather included between the outline of said heel and the dotted line 4 is saved in the initial cost of the shoe. This is a material item. 85

An outsole such as above described is shown attached to an upper as at 5 in the usual way, and to which no claim is made.

At this point in the shoe building operation the heel portion 2 is loose and not positively secured to the upper. The securing of this portion of the sole to the shoe is by means of applying the heel thereto and passing a screw or nail from the inside through the wood of the heel. 90

In order to apply the wood block heel 6 it is obviously necessary that a portion of the heel portion 2 indicated by cross hatching and the numeral 7, must be removed therefrom in order to allow the outer edge of the 100 heel 6 to lie adjacent the shoe upper at this point. As has been above stated, this is usually done by hand, and requires a considerable length of time.

In carrying out my invention the operator 105 places the heel in its final desired position

and draws a mark with a sharp instrument across the breast of the heel adjacent the outsole. The shoe thus marked is then placed in a power machine of any desired type and to which no claim is made, in which is arranged an anvil comprising a shaft 8 secured in the machine, to the end of which is attached the anvil proper 9. This anvil is preferably of metal for a purpose more fully 10 described hereinafter.

Above the anvil and arranged for vertical reciprocal movement is a knife comprising an arc shaped blade 10 and two backwardly extending blades 11, the latter blades to cut 15 from the heel portion 2 of the outsole the tail portion above referred to. That portion of the curved blade between the backwardly extending blades 11 is cut away and provided with a flat face 12, the difference in 20 level between the face 12 and the edges of the blades 10 and 11 being equal to the normal thickness of the outsole at the breast of the heel.

The shoe at this stage of its structure is 25 moved forward so that the anvil extends under the heel portion 2 of the outsole and then by suitable mechanism (not shown) the knife is made to move downward vertically so that the arc shaped blade 10 strikes the 30 outsole along the line indicated on the outsole as being the location of the heel breast. This downward movement of the blade will continue until the flat face 12 engages the surface of the outsole, when further downward movement of the blade will be prevented thereby. At this point the blades 10 35 and 11 will have penetrated the outsole and severed off the pieces 7 so as to form the tail piece 2^a. The operator will then slightly

bevel the edges of the tail piece with his 40 knife, upon which it will be found that the heel 6 will exactly fit the curvature made by the arc shaped blade 10 and the heel may then be secured to the shoe as in the ordinary manner. It will be noted in such 45 a structure that the loose end of the outsole, namely the tail piece 2^a, is rigidly held by reason of the fact that it underlies the heel 6, or it may be tacked fast to the innersole or the shank piece, to which no claim is 50 made.

Having thus described my invention, what I claim is:—

1. A die for fitting heels to shoes, including an arc-shaped blade of the curvature of 55 the heel breast, said arced portion being interrupted by a non-cutting portion, and two straight blades extending backwardly from the arc-shaped portion at each end of the non-cutting portion.

2. A die for fitting heels to shoes, including an arc shaped blade and two straight blades extending backwardly therefrom, that portion of the die between the straight 60 edges constituting a raised flat face.

3. A die for fitting heels to shoes, including an arc shaped blade and two straight blades extending backwardly therefrom, that portion of the die between the straight edges constituting a raised flat face, the difference in level between the edges of the 65 blades and the bottom of the flat face being equal to the thickness of the outsole at the 70 normal location of the heel breast.

In testimony whereof, I affix my signature.

WILLIAM HEDGES TAYLOR.
